UNITED STATES PATENT OFFICE

104,565

DESIGN FOR A GLIDER OR SIMILAR ARTICLE

Eugene G. Fischbach and Robert W. Sumey,
Pueblo, Colo.

Application March 2, 1937, Serial No. 67,948

Term of patent 3½ years

To all whom it may concern:

Be it known that we, Eugene G. Fischbach and Robert W. Sumey, citizens of the United States, residing at Pueblo, in the county of Pueblo and State of Colorado, have invented a new, original, and ornamental Design for a Glider or Similar Article, of which the following is a specification, reference being had to the accompanying drawing, forming part thereof.

Figure 1 is a front elevation of a glider showing our design; and

Figure 2 is a side elevation of the glider illustrated in Figure 1.

We claim:

The ornamental design for a glider or similar article, as shown.

EUGENE G. FISCHBACH.

ROBERT W. SUMEY.
